UNITED STATES PATENT OFFICE

147,595

DESIGN FOR A BELT BUCKLE OR THE LIKE

Albert Nalick, Los Angeles, Calif.

Application December 20, 1946, Serial No. 135,655

Term of patent 3½ years

(Cl. D17—1)

To all whom it may concern:

Be it known that I, Albert Nalick, a citizen of the United States, residing at Los Angeles, in the county of Los Angeles and State of California, have invented a new, original, and ornamental Design for a Belt Buckle or the like, of which the following is a specification, reference being had to the accompanying drawing, forming part thereof.

Fig. 1 is a front elevational view of a belt buckle or the like showing my new design.

Fig. 2 is a side edge view thereof, the essential features being shown in full lines.

I claim:

The ornamental design for a belt buckle or the like, substantially as shown and described.

ALBERT NALICK.
